UNITED STATES PATENT OFFICE.

CHARLES F. WALTHER, OF BUFFALO, NEW YORK.

DESIGN FOR A RADIATOR.

SPECIFICATION forming part of Design No. 24,644, dated August 27, 1895.

Application filed August 1, 1895. Serial No. 557,905. Term of patent 7 years.

To all whom it may concern:

Be it known that I, CHARLES F. WALTHER, a citizen of the United States, residing at Buffalo, in the county of Erie and State of New York, have invented a certain new, useful, and original Design for Radiators; and I do declare the following to be a full, clear, and exact description of the invention, such as will enable others skilled in the art to which it appertains to make and use the same, reference being had to the accompanying drawing, and to the letters of reference marked thereon, which forms a part of this specification.

This design has for its object to give to a radiator for steam and hot-water heating a new and original configuration, and to ornament the exposed surfaces of the radiator, whereby it is given a distinctive and artistic appearance.

The accompanying drawing is a perspective view of a radiator made according to my present design.

The following are the characteristic features of my design. The radiator sections or loops are formed at each edge and near their tops with knobs or projections A, so that the radiator is provided with rows of these knobs adjacent to the upper ornamented part of the

radiator, and as clearly indicated in the drawing.

Another distinctive feature of the design is produced by forming the loops or sections with the pointed ornament B at the top, so that the radiator comes to a point at the top, as distinguished from having a flat top.

Another distinctive feature of my design is the slender vine ornamentation C, which is arranged near the edges of the loops or sections and connects the ornamentations at the bottom of the radiator with the ornamentations at the top thereof.

Other distinctive features of my design are the roccoco ornamentation D at the top of the radiator, and the Louis XIV ornamentations E at the ends of the radiator.

Having thus described my new and original design, what I claim, and desire to secure by Letters Patent, is—

The design for a radiator, substantially as shown and described.

In testimony whereof I affix my signature in presence of two witnesses.

CHARLES F. WALTHER.
